DESIGN FOR A GLOVE

Charles E. Zimmerman, Chicago, Ill.

Application July 11, 1945, Serial No. 120,651

Term of patent 3½ years

(Cl. D3—11)

To all whom it may concern:

Be it known that I, Charles E. Zimmerman, a citizen of the United States, residing at Chicago, in the county of Cook and State of Illinois, have invented a new, original, and ornamental Design for Glove, of which the following is a specification, reference being had to the accompanying drawing, forming a part thereof.

In the drawing:

I claim:

The ornamental design for a glove, substantially as shown.

CHARLES E. ZIMMERMAN.
